UNITED STATES PATENT OFFICE.

HAROLD E. WHITE, OF SCHENECTADY, NEW YORK, ASSIGNOR TO GENERAL ELECTRIC COMPANY, A CORPORATION OF NEW YORK.

CONTROLLING-SWITCH.

No. 882,602.

Specification of Letters Patent. Patented March 24, 1908.

Application filed September 18, 1908. Serial No. 335,051.

To all whom it may concern:

Be it known that I, HAROLD E. WHITE, a citizen of the United States, residing at Schenectady, county of Schenectady, State 5 of New York, have invented certain new and useful Improvements in Controlling-Switches, of which the following is a specification.

My invention relates to controlling switches employing blow-out magnets and is 10 particularly applicable to motor controllers. It is frequently desirable that the arc formed at each contact-finger should always be blown in the same direction, and since the current through the contact-fingers may be 15 reversed in different positions of the switch, it has been proposed heretofore, in order to secure the desired result, to provide individual blow-out coils for each of the fingers, each 20 of which is connected directly in series with its finger, so that when the direction of current through the finger reverses, the direction of current through the blow-out coil will also be reversed. When individual blow-outs are employed it may sometimes happen 25 that adjacent coils may have a difference of voltage equal to the entire voltage of the system; and consequently it is necessary to provide insulation adapted to withstand this voltage. To secure in a compact structure 30 both an efficient magnetic circuit and the necessary insulation so disposed as to permit unobstructed movement to the expanding arc, presents problems which it is the object of my invention to solve.

35 My invention in one aspect consists in separating the main poles of the blow-out coils from the coils themselves by insulation and providing auxiliary pole-pieces for inductively magnetizing the main poles. By 40 the use of these auxiliary pole-pieces an efficient magnetic circuit may be secured, while at the same time the insulation between each coil and its main pole-piece serves effectively to insulate adjacent blow- 45 out coils from each other.

My invention will best be understood by reference to the accompanying drawings, in which

Figure 1 shows an elevation, partly in 50 cross-section, of a motor controller arranged in accordance with my invention; Fig. 2 shows a plan view of the same; and Fig. 3 a detail view in perspective.

In the drawings, A represents the controller drum carrying the movable contacts.

B represents the stationary contact-fingers engaging the drum.

C represents the blow-out coils, one of which is provided for each finger, and which are arranged with their axes parallel to the 60 axis of the drum A. These coils are each connected between a finger B and the terminal D, to which the connecting lead for the finger is brought, so that when the current through any finger is reversed the magnetic field produced by the corresponding coil is also reversed. The coil C may be conveniently wound of a copper strip. The outer turn may be connected to the terminal post D, as shown in Fig. 2, while the inner turn 70 may be conveniently connected to the contact-finger B by connecting it to the core c of the coil, which is electrically connected to the contact-finger B by the iron plates E, which, beside forming the electrical connection between the coil and the finger, serve as the auxiliary or primary pole-pieces of the coil. These plates, which are in both magnetic and electrical contact with the core c, extend in a plane perpendicular to the core 75 over only a portion of the length of the contact-fingers. The main pole-pieces F are molded into slabs of insulation G and extend parallel to the primary pole-pieces E into proximity to the points of contact of the contact-fingers and the controller drum. These main or secondary pole-pieces F are thus insulated from the blow-out coils and contact-fingers, and are separated by the insulation 80 from the cores of the blow-out coils; but are 90 inductively magnetized by the primary pole-pieces E. Since the air-gap between the pole-pieces E and F is of large cross-section and small length, an efficient magnetic circuit is secured, while at the same time each 95 coil and finger are effectively insulated from the adjacent coils and fingers.

In order to permit free access to the contact-fingers for the purpose of inspection and renewals the insulated slabs G carrying the 100 main pole-pieces are secured to a support H, which is pivotally mounted within the casing so that all of the main pole-pieces may be swung outward, as shown in Fig. 2.

The several coils are preferably so arranged 105 that the direction of the arc, under the influence of the blow-out field, is as indicated by the arrow in Fig. 2. It will be seen that a large space is provided in this direction, through which the arc may move without 110

coming into contact with any other parts of the controller, thus fulfilling one of the important conditions mentioned above. Furthermore, when the controller is being moved 5 toward off-position, or counter-clockwise as viewed in Fig. 2, the arc is blown away from the drum contacts, instead of traveling along them, as would be the case if the direction of blow-out were reversed, and thus their de-
terioration from a traveling arc is avoided.

What I claim as new and desire to secure by Letters Patent of the United States, is,—

1. In a controlling switch, in combination with a rotary drum and contact-fingers engaging therewith, individual blow-out coils connected directly in series with the several fingers, auxiliary pole-pieces in magnetic contact with the cores of said coils, and main pole-pieces separated from the auxiliary pole-
pieces by insulation and magnetized inductively thereby.

2. In a controlling switch, in combination with a rotary drum and contact-fingers engaging therewith, individual blow-out coils connected directly in series with the several fingers, auxiliary pole-pieces in magnetic contact with the cores of said coils, main pole-pieces separated from the auxiliary pole-pieces by insulation and magnetized inductively thereby, and means for so supporting said main pole-pieces that they are movable away from the coils to give access to the fingers.

3. In a controlling switch, in combination with a rotary drum and contact-fingers engaging therewith, individual blow-out coils connected directly in series with the several fingers, auxiliary pole-pieces in magnetic contact with the cores of said coils, main pole-pieces separated from the auxiliary pole-pieces by insulation and magnetized inductively thereby, and a pivotally-mounted member supporting the main pole-pieces.

4. In a controlling-switch, in combination with a rotary drum and contact-fingers engaging therewith, individual blow-out coils connected directly in series with the several fingers, one end of each coil being connected to its core, auxiliary pole-pieces in magnetic and electrical contact with the cores of said coils, and main pole-pieces separated from the auxiliary pole-pieces by insulation and magnetized inductively thereby.

5. In a controlling switch, in combination with a rotary drum and contact-fingers en-

gaging therewith, individual blow-out coils connected directly in series with the several fingers, the inner turn of each coil being connected to its core, auxiliary pole-pieces in magnetic and electrical contact with the cores of said coils, main pole-pieces separated from the auxiliary pole-pieces by insulation and magnetized inductively thereby, and means for so supporting said main pole-pieces that they are movable away from the coils to give access to the fingers.

6. In a controlling switch, in combination with a rotary drum and contact-fingers engaging therewith, individual blow-out coils for the several fingers each wound with a conducting strip having one end connected on the core; auxiliary pole-pieces in magnetic and electrical contact with the cores of said coils; and in electrical contact with the fingers, and main pole-pieces separated from the auxiliary pole-pieces by insulation and magnetized inductively thereby.

7. In a controlling switch, in combination with a rotary drum and contact-fingers engaging therewith, individual blow-out coils for the several fingers mounted with their axes parallel with the axis of the drum, auxiliary pole-pieces in magnetic contact with the cores of the coils and extending in planes perpendicular to their axes, and main pole-pieces in planes parallel with the auxiliary pole-pieces but separated therefrom by insulation and extending into proximity to the contact points of the fingers.

8. In a controlling switch, in combination with a rotary drum and contact-fingers engaging therewith, individual blow-out coils for the several fingers mounted with their axes parallel with the axis of the drum, auxiliary pole-pieces in magnetic contact with the cores of the coils and extending in planes perpendicular to their axes, and main pole-pieces in planes parallel with the auxiliary pole-pieces but separated therefrom by insulation and extending into proximity to the contact points of the fingers, the coils and pole-pieces being arranged to drive the arcs between the fingers and drum contacts in a direction away from the coils.

In witness whereof, I have hereunto set my hand this 17th day of September, 1906.

HAROLD E. WHITE.
